(57) **CLAIM**

The ornamental design for a display screen with icon, as shown and described.

DESCRIPTION

FIG. 1 is a front view of a display screen with icon showing the new design; and,

FIG. 2 is a front view of an alternative embodiment of a display screen with icon with the icon being a mirror image of the icon of FIG. 1.

The broken line showing of the Swoosh trademark and the display screen is for environmental purposes only and forms no part of the claimed design.

1 Claim, 2 Drawing Sheets

FIG. 1

FIG. 2
